UNITED STATES PATENT OFFICE.

THEODORE E. LA FAYETTE, ALFRED A. GLIDDEN, AND JOHN J. GAUGHAN, OF WATERTOWN, MASSACHUSETTS, ASSIGNORS TO HOOD RUBBER COMPANY, OF WATERTOWN, MASSACHUSETTS, A CORPORATION OF MASSACHUSETTS.

RUBBER FOOTWEAR.

Application filed December 30, 1920. Serial No. 434,042.

To all whom it may concern:

Be it known that we, THEODORE E. LA FAYETTE, ALFRED A. GLIDDEN, and JOHN J. GAUGHAN, citizens of the United States, 5 and residents of Watertown, in the county of Middlesex and State of Massachusetts, have invented certain new and useful Improvements in Rubber Footwear, of which the following is a specification.

10 Our present invention relates to improvements in rubber footwear, and aims to simplify the construction and reduce the number of parts thereby effecting a saving of merchandise and the labor required in 15 the making of the article. We have further aimed to produce a construction of great flexibility and elasticity whereby overshoes embodying our invention will have a greater range of adaptability to shoes of different 20 sizes, enabling the manufacture of half sizes and many widths to be eliminated, and we have also aimed to provide a construction which will not be liable to open up and leak at the edge of the sole.

25 We have in the present application selected the foot-hold type of overshoe to illustrate an embodiment of our invention although it will be understood that we do not limit ourselves in this respect, the main 30 features of the invention being applicable to any type or style of rubber footwear.

In foot-holds as heretofore manufactured it has been customary to build these up on a last from a considerable number of 35 pieces. These include the following parts, (1) an upper lining, (2) a gum upper or covering, (3) an insole stay, (4) a heel piece or strap, (5) a toe piece or tip, (6) an out-sole stay, (7) a sole filler, (8) an insole 40 and (9) an outer sole. These are applied successively by hand and rolled down by a squeegee or pressing roller, the usual method being to place the insole on the last bottom, stretch the lining snugly over the last and 45 secure its edge adhesively to the insole, apply the filler, coat the lining with a rubber cement and then apply the gum upper or covering, whereafter the out-sole, toe, tip, and strap are individually applied, the 50 parts as they are successively applied being rolled down or pressed together and against the last by a hand roller to secure firm adherence and a smooth exterior surface.

This requires a large number of distinct operations and the use of parts which it is 55 one of the objects of the present invention to materially reduce.

Furthermore, in such a shoe all the parts join at or near the edges of the sole in a distinct corner which must accurately fit the 60 sole of the shoe upon which the overshoe is worn, therefore elasticity or stretchability in the soles of such overshoes is undesirable, and there is always a tendency 65 of cracking or breaking of the overshoes at the joints, which objection is eliminated by the present invention.

With these and other objects in view which will hereinafter appear, our invention includes the novel article as hereinafter 70 described and particularly defined by the appended claims.

An embodiment of our invention is illustrated in the accompanying drawings in 75 which:

Figure 1 is a plan view of the upper blank.

Figure 2 is a similar view of the filler blank.

Figure 3 is a plan view of a section of 80 the binding strip.

Figure 4 is a plan view of the sole and heel strap blank and

Figure 5 is a similar view of the toe cap.

Figure 6 is a side elevation of the assem- 85 bled parts in place upon a last.

Figure 7 is a plan view of the foot-hold removed from the last, and

Figure 8 is a transverse section looking 90 towards the toe.

In making up a foot-hold according to our present invention we use but five parts of pieces as shown in the figures of sheet 1 of the drawings.

The part 1 is of elastic fabric coated with 95 rubber gum and may be cut to the desired shape, such as shown for example in Fig. 1, by a cutting die, the shape being such that when its edges 1^a are joined in a suitable manner a pocketed construction, so to speak, 100 is formed, which is then drawn upon a last 6, the seam formed by the joined edges lying centrally of the bottom of the last.

The elastic fabric may be of any suitable 105 nature, such for example, as stockinette, knitted fabric or a specially woven elastic

fabric, having sufficient elasticity to enable it to be drawn over the last and shape itself perfectly thereto by its inherent elasticity.

The seam or junction may be conveniently 5 formed by joining together the abutting edges by sewing, stitching or other suitable means, and the seam being flattened or smoothed out in any suitable manner as indicated at *a* in Fig. 8. If desired the seam 10 or junction may be at any location other than that indicated in Figures 7 and 8.

The portions of the upper which extend underneath the bottom of the last constitute in effect an inner sole, to which is applied 15 the filler, indicated at 2, the filler adhering to the unvulcanized rubber surface so that no cement is necessary.

From a sheet of stock, run on an engraved 20 calender roll to give to one side a beaded or otherwise suitably configured surface, we cut, by a suitable die, a blank of the shape shown in Figure 4, having a front portion 4^a conforming to the sole of the last and having a widened out rear portion 4^b provided with a central opening 4^c. The portion of the blank around this opening constitutes the back or heel strap which is designated at 4^d, (Figs. 6 and 7), the edges of 25 which are preferably folded or curled over as indicated at *d* to give a finished effect. If preferred, the calender roll can be so engraved that a bead will be formed at the edges of the strip thereby avoiding the necessity of folding or curling over the edges.

30 The toe cap is next applied as indicated at 5 in Figures 6 and 7.

The smooth side of the sole is applied to the bottom of the last and pressed firmly 35 against the filler and upper, the edge of the sole being preferably carried slightly up over the sides, as shown, and the strap portion stretched or carried up over the heel portion of the last in proper position.

Thereafter the binding strip is applied as indicated at 3, and the shoe is varnished and 45 vulcanized in the usual manner.

By reducing the number of parts we not only effect a saving in merchandise cost and reduce the number of labor operations in building up the shoe as will be apparent 50 from the foregoing, but effect a corresponding reduction in the preparatory manufacturing processes, which effects a material saving in labor.

Furthermore, the shoe produced by our 55 process is free from the joints and sharp corners at the edges of the sole and is stretchable thereby enabling us to eliminate half sizes and widths and yet secure effective fits.

While we have selected a foot-hold as a convenient and desirable embodiment of our invention it should be understood that, in its broader aspects, it is not limited to this type of shoe, being applicable to any type 65 of rubber footwear, and where in this specification, we use the term "rubber shoe" it is to be understood as inclusive of any article of footwear composed of fabric and rubber compounds.

Having thus described our invention 70 what we claim is:

An article for forming the upper and heel strap of a rubber overshoe of the foot-hold type comprising a blank of fabric of 75 substantially elliptical shape having a widened-out rear portion provided with a central opening, the rear edge of the blank being substantially concentric to the rear edge of said opening.

In testimony whereof, we affix our signatures.

ALFRED A. GLIDDEN.
THEODORE E. LA FAYETTE.
JOHN J. GAUGHAN.
